UNITED STATES PATENT OFFICE.

ROLANDIS A. BLAIR, OF FORT WAYNE, INDIANA.

RAIL ANCHOR.

Application filed December 9, 1927. Serial No. 238,818.

My invention relates to rail anchors and has for its object the provision of a new and improved form and arrangement of parts by which an anchor can be secured firmly upon a rail so that by engagement with a cross tie or other fixed part of a track the rail will be held from movement longitudinally of itself. It is one of the objects of my invention to provide an improved form of device by which the required gripping effect may be attained for holding the rail with respect to the tie by the use of a minimum amount of metal, by which the device shall be held most strongly against being twisted from the rail upon the application of heavy pressure to the device, and by which there shall be a novel combination gripping effect upon the rail. To this end, it is one of the objects of my invention to provide an anchor which engages the tie at only one end portion so as to have a lever gripping effect upon the rail about a vertical axis, which is provided with two gripping jaws spaced longitudinally of the rail so that as pressure is applied upon the anchor below the level of the rail there is a lever gripping effect upon the rail about an axis extending transversely of the rail, which is arranged so that there shall be a lever gripping effect upon the rail about an axis extending longitudinally of the rail brought about by the application of the anchor to the rail, and in which one of the gripping jaws when distorted in the direction of the pressure is caused to grip the rail more tightly upon the edge of the flange as the pressure is increased.

It is another object of my invention to provide an anchor having a new arrangement of gripping and retaining means by which the gripping jaws at one side of the rail are held in lever gripping engagement with a rail flange by a transverse arm having an upwardly extending portion which stands in contact with the bottom face of the rail when the jaws are moved to the limit of their movement into position on the flange by transverse pressure applied opposite the edge of the flange and which snaps into holding engagement with the side face of the flange when the jaw members are swung inwardly toward the rail by pressure applied at the bottom portion of the member. It is one of the objects of my invention to provide a construction of this type in which the jaws are held in lever gripping engagement with the flange by the spring action of the arm prior to the final swinging movement of the jaw member for permitting

the snap engagement of the arm with the side face of the flange. It is another object of my invention to provide such a structure in which the final effective lever grip is brought about by the swinging movement of the jaw member in opposition to the spring action of said arm, the arm serving by its engagement with the side face of the flange to prevent swinging movement in the reverse direction and serving thus by its tensile strength to hold the jaws in their lever gripping position. It is another object of my invention to provide an improved anchor comprising a gripping jaw which normally stands at a slight angle with respect to a line extending transversely of the rail and arranged so that the change in the position of the jaw brought about by pressure thereon in use shall have the effect of further tightening the device on the rail.

It is another object of my invention to provide an improved form of rail anchor made from a single piece of metal and provided with two rail abutments which can be used to equal advantage for engagement with the cross tie, making it unnecessary to produce both right-hand and left-hand constructions. It is still another object of my invention to provide a novel construction in which the parts which are distorted by the application of the anchor to a rail are so arranged that the necessary distortion is distributed to different portions of the device sufficiently to prevent permanent distortion at any point.

It is still another object of my invention to improve devices of this type in sundry details hereinafter pointed out. The preferred means by which I have accomplished my several objects are illustrated in the drawings and are hereinafter specifically described. That which I believe to be new and desire to cover by this application is set forth in the claims.

In the drawings,—

Fig. 1 is a face view of the preferred form of my improved anchor in its initial position upon a rail shown in section and partly broken away.

Fig. 2 is a view similar to Fig. 1 but showing the position of the parts when the gripping jaws have been driven evenly into preliminary gripping position upon the flange.

Fig. 3 is a view similar to Fig. 2 but showing the anchor in its final operative position.

Fig. 4 is a top view of the parts as shown in Fig. 3, and showing in dotted lines a changed position of the gripping jaw next

to the cross tie such as might be produced by heavy pressure of the device against the tie.

Fig. 5 is a view similar to Fig. 1 but showing a modified form of construction.

Fig. 6 is a view similar to Fig. 5 but showing the anchor in its finally applied position.

Fig. 7 is a view similar to Fig. 1 but showing a further modified form.

Fig. 8 is a view similar to Fig. 7 but showing the anchor in its completely applied position; and

Fig. 9 is a top plan view of the anchor shown in Fig. 7.

Referring now to Figs. 1 to 4 inclusive, in which corresponding parts are indicated by the same reference characters,—10 indicates a rail mounted upon a cross tie 11 with a tie plate 12 of any approved type interposed therebetween. Upon one edge of the flange 20 of the rail 10, I have mounted the preferred form of my improved anchor, the anchor being loosely applied in its initial position in Fig. 1.

The anchor as shown in Figs. 1 to 4 comprises a plate of sheet metal 13 having a transverse bar 14 formed integrally therewith and bent over in a gradual curve toward one face of the plate. Jaw members 15, also formed integrally with the plate 13, are bent over into position at opposite sides of the transverse bar or arm 14, such jaw members 15 normally standing in divergent position with respect to each other and in equally divergent position with respect to the arm 14. Each of the jaw members 15 is notched at its free vertical edge, providing jaws 16 and 17 adapted to engage the top and bottom faces respectively of the flange of the rail 10. As is clearly shown in Fig. 1, the arrangement is such that the arm 14 before application of the anchor to a rail normally stands opposite the notches so as to prevent the jaw members from being applied to the flange of the rail for which they are designed for use except upon the application of pressure to the parts serving to displace the arm 14 from normal position. At its free end, the arm 14 is provided with an upturned portion 18 which is adapted in the final operative position of the anchor to engage the edge of the flange of the rail at the side opposite that at which the head of the anchor is located.

In the application of the device as illustrated in said Figs. 1 to 4 to a rail, it is first placed loosely in position as shown in Fig. 1. The jaw members 15 are then driven evenly into engagement with the flange into about the position shown in Fig. 2, by the application of pressure on the outer face of the head 55 at a point opposite the edge of the flange of the rail. In this position, the end face of the notch between the jaws 16 and 17 stands preferably in engagement with the edge face of the flange of the rail, and the upturned portion 18 of the arm 14 stands in engagement

with the bottom face of the rail, the driving being resorted to for displacing the arm 14 downwardly with respect to the jaw members 15. In this position of the parts, the upper jaw 16 of the device stands preferably at 70 about the same angle as that of the upper face of the flange of the rail, while the lower jaw 17 engages the bottom face of the flange throughout the full length of the jaw. For completing the application of the device to 75 the rail, pressure is applied upon the outer face of the head member near the bottom portion thereof, preferably by the use of a sledge, for giving the head member a swinging movement in counter-clockwise direction from the 80 position shown in said Fig. 2 about an axis extending longitudinally of the rail, so as to cause the jaws 16 and 17 to have a very strong lever grip upon the flange of the rail transversely thereof, the jaws 17 pressing upwardly at their end portions at the right in Fig. 3 at the points indicated by the numeral 19, and the jaws 16 pressing downwardly. The arrangement is such that the maximum 85 of downward pressure is applied at the points indicated by the numeral 20 at the shoulders located at the inner ends of the effective bearing portions of the jaws 16, such points being located at a substantial distance toward the left in said Fig. 3 as compared with the points 90 of bearing of the jaws 17 on the bottom face as above described, whereby an effective lever grip is attained. This turning of the head of the device about an axis extending longitudinally of the rail serves in effect to increase 95 the length of the arm 14 with respect to the flange of the rail, serving to permit the upturned portion 18 of the arm to snap into engagement with the edge of the flange at the side thereof opposite that on which the jaws 100 are mounted, the arrangement being such that the snap engagement of the arm with the flange is effected without any material loosening of the jaws on the flange. The arm 14 thereafter serves by its continued engagement with the flange effectually to prevent rotary movement of the head in the opposite direction, the arm being comparatively rigid longitudinally thereof for effecting this result. By its engagement with the bottom 105 face of the rail at both sides thereof as shown in Fig. 3, the arm 14 materially strengthens and reinforces the grip of the anchor.

By the provision of my construction, in which the gripping head is driven initially 120 into engagement with the flange of the rail until the end face of the notch stands in contact with the edge face of the flange, a workman is effectually prevented from over-driving the device during the preliminary driving operation. When the gripping head is being given its swinging movement about a longitudinal axis from its preliminary gripping position as shown in Fig. 2 to its final 125 operative lever gripping position as shown 130

in Fig. 3, the driving operation is kept up only until the arm 14 with its upturned portion 18 has snapped securely into engagement with the flange. This feature of my invention serves effectively to protect my device against distortion by the workman in the application of the device.

The clearance between the jaws and the flange of the rail at its outer edge is designed for permitting the swinging movement of the head of the anchor for bringing the jaws into lever gripping engagement with the rail and for making possible the holding engagement of the arm 14 with the opposite edge 15 face of the flange. The shoulder 20 at the inner end of the jaw 16 is positioned with reference to its effective cooperation with the corner 19 of the jaw 17 for attaining the desired lever grip.

By reason of the fact that the jaws diverge from the edges at which they are connected with the intermediate plate 13, any heavy pressure between the cross tie and the abutment plate or jaw member tends to swing the plate toward the transverse arm 14 into some such position as that shown by dotted lines in Fig. 4. As will be readily understood, if the anchor is effectively tightened upon the rail with the abutment plate adjacent to the cross tie in the normal position indicated by the solid line position of the plate 15 in said Fig. 4, the swinging movement of the plate from such an angle to the changed angle as indicated serves quite materially to tighten 35 the anchor upon the rail.

With the jaw members 15 in spaced relation longitudinally of the rail and both gripping the edge of the flange very tightly as above described, and with the cross tie 11 spaced some little distance below the rail through the use of the tie plate 12, the pressure applied upon the lower end portion of the gripping head of the anchor by contact with the tie at that point serves to apply a very strong 45 lever grip about a transverse axis, with the jaw member 15 pressing downwardly on the flange adjacent to the tie and the other jaw member 15 pressing upwardly. With the upturned portion 18 of the arm engaging the edge of the flange at the right as shown in the several figures, and with the pressure between the anchor and the tie being applied all at one end of the device, the anchor will have a distinct tendency to apply a heavy lever 55 grip upon the rail about a vertical axis located between the upturned portion 18 and the bearings upon the edge of the flange at the opposite side of the rail, with the end face of the notch in the jaw member 15 farther from the tie pressing toward the right in Fig. 4 and the forward edge of the upturned portion 18 pressing toward the left.

When it is desired to remove the anchor from the rail, this can be effected by driving 65 downwardly and toward the axis of the rail

upon the upturned portion 18 of the arm 14. By reason of the fact that the gripping jaws are substantially rigid vertically and of the fact that the only part of the device which is substantially displaced by the application of the device to a rail is the arm 14 which is arranged flatwise with respect to the rail, it will be appreciated that the danger of permanent distortion of the device is very small. It will be appreciated also that by 75 reason of my novel arrangement the anchor can be applied to a rail and removed therefrom a great number of times without destroying its effectiveness for gripping the rail for which it was originally designed. By 80 reason of the gradual curvature of the arm 14 at the point where it is connected with the plate 13, the distortion is distributed throughout the length of the arm and that at any one point is very small so as substantially to prevent any danger of permanent distortion.

The construction shown in Figs. 5 and 6 is of the same type as that shown in Figs. 1 to 4, in that it comprises jaw members 15 90 adapted to be driven into preliminary gripping position upon the rail 10 by pressure applied substantially opposite the edge of the flange of the rail, with a transversely extending arm or bar adapted at the end of the 95 preliminary driving operation to stand in engagement with the bottom face of the rail until the head of the device has been given a slight rotary movement for permitting the arm or bar to snap into engagement with the 100 edge of the flange as above described. The operation of the device of Figs. 5 and 6 is, however, somewhat different.

In the construction shown in Figs. 5 and 6, the jaw members 15 are formed integrally 105 with a plate 13 with which the arm or bar 21 is also formed integrally, the bar 21 corresponding to the bar 14 of the first described construction. The bar 21 is coupled with the head of the anchor at a point comparatively much higher than the point at which the arm 14 is coupled with the head of the device of Figs. 1 to 4. The free edges of the jaw members 15 are notched for providing jaws 16 and 17, clearance being provided at 110 the upper face of the flange opposite its outer edge as in the first described construction.

When the anchor is applied to the rail 10 and driven into its preliminary gripping position as shown in Fig. 5, the jaws 16 and 17 are caused to exert an effective lever grip upon the rail flange 10 by reason of the displacement of the arm 21 downwardly, such arm 21 being adapted normally to stand in position opposite the notches in the free edges of the 120 jaw members 15. In this preliminary gripping position, the end of the notch stands in engagement with the edge of the flange of the rail in substantially the same way as is illustrated in Fig. 2 in connection with the device 125 130

there shown. In the preliminary gripping position of the anchor as illustrated in Fig. 5, the maximum downward pressure by the jaw 16 is effected at the point 22 at the shoulder 6 located at the inner end of the effective bearing portion of the jaw 16. The maximum upward pressure in the preliminary gripping position as shown in said Fig. 5 is applied at the point 23 located at the inner end of the 10 jaw 17. When pressure is applied at the bottom portion of the head for forcing such bottom portion inwardly toward the rail, the downward pressure at the point 22 and the upward pressure at the point 23 are relieved 15 slightly by the turning movement of the head for permitting the upright portion 24 on the end of the arm 21 to snap into holding engagement with the edge of the flange of the rail. Following the snap engagement of the 20 arm with the edge of the flange, the jaw members are permitted to rotate again in clockwise direction into the position shown in Fig. 6 in which the jaw members once more are held by the resilient arm 21 in lever gripping 25 engagement with the flange of the rail, the major downward pressure again being at the point 22 and the major upward pressure being again at the point 23. The position of the point 22 is regulated by reference to the 30 position of the point 23 for producing an effective lever grip in the manner specified. The head of the anchor is permitted after the snap engagement of the arm 21 with the edge of the flange to return to substantially the 35 same position as shown in Fig. 6 as that formerly occupied by the head as shown in Fig. 5 by reason of the comparatively high coupling of the arm 21 with the head, the length of the arm 21 being regulated for permitting 40 the operation as described.

In the construction shown in Figs. 7, 8 and 9, the arm 25 formed integrally with the plate 26 of the head of the device is turned backwardly in the opposite direction from that in 45 which the jaw members 27 are turned, the notches for receiving the edge of the rail flange being formed in the edges of the jaw members 27 adjacent to the point where such jaw members are connected with the plate 50 26 rather than at their free edges as in the construction shown in Fig. 1. The construction as shown in Figs. 7, 8 and 9 follows that of the device shown in Figs. 1 to 4 more closely than that shown in Figs. 5 and 6, in that 55 in the construction of Figs. 7, 8 and 9 the transverse arm 25 is coupled with the head of the anchor at a comparatively low point, and the length of the arm 25 is such as to permit the upturned portion 28 to snap into holding 60 engagement with the edge of the flange only when the jaw members 29 and 30 have been turned in counter-clockwise direction in Fig. 8 into lever gripping engagement with the flange of the rail. It will be understood accordingly that in the construction of Fig. 8

the maximum downward pressure is applied at the point 31 at the inner end of the effective portion of the upper jaw 29 and that the maximum upward pressure is applied at the point 32 located at the corner of the jaw 30 70 at the outer end of the jaw. In this construction, by reason of the length of the arm 25 and the low coupling of the arm with the head of the anchor, the head is held against rotation to any material extent in clockwise 75 direction after the snap engagement of the arm 25 with the edge of the flange.

While I prefer to employ the construction as disclosed by my drawings and as above described, I do not wish to limit my invention thereto except so far as certain of the claims may be specifically so limited by reference to the prior art, since it will be understood that changes may well be made in my construction without departing from the spirit 80 of my invention. While I have described the jaw members as being rigid vertically, it will be understood that such description is used in its relative sense to mean that under conditions of use as contemplated the yielding, 85 if any, is so small as to have no material effect on the results.

I claim:

1. A rail anchor comprising in combination a jaw member having jaws for engaging the top and bottom faces of the flange at one side of a rail and arranged for permitting a slight angular movement of the jaw member with respect to the flange about an axis extending longitudinally of the rail for exerting an effective lever grip on the flange transversely thereof, and a resilient arm connected with said jaw member in position to extend underneath the rail and having an upturned end portion adapted when the jaw member is 105 moved to the limit of its motion into position on the flange by transverse pressure applied opposite the edge of the flange to stand in contact with the bottom face of the flange and adapted when the jaw member is thereafter swung inwardly toward the rail by pressure applied at the lower end portion of the member to snap into holding engagement with the edge of the flange, said arm being adapted by its bearing on the rail to hold said 110 jaw member in turned lever gripping engagement with the flange.

2. A rail anchor comprising in combination a jaw member having jaws for engaging the top and bottom faces of the flange at one side of a rail and having clearance with respect to the flange at opposite sides of the effective bearing portions of the jaws for permitting a slight rotary movement of the jaw member about an axis extending longitudinally of the rail for exerting an effective lever grip on the flange, and a resilient arm connected with said jaw member in position to extend underneath the rail and having an upturned end portion adapted when the jaw 125

- member is moved to the limit of its motion into position on the flange by transverse pressure applied opposite the edge of the flange to stand in contact with the bottom face of the flange and adapted when the jaw member is thereafter swung inwardly toward the rail by pressure applied at the lower end portion of the member to snap into holding engagement with the edge of the flange, said arm being adapted by its bearing on the rail to hold said jaw member in turned lever gripping engagement with the flange.
3. A rail anchor comprising in combination a jaw member having jaws in rigid spaced relation to each other for engaging the top and bottom faces of the flange at one side of a rail and arranged for permitting a slight angular movement of the jaw member with respect to the flange about an axis extending longitudinally of the rail for exerting an effective lever grip on the flange transversely thereof, and a resilient arm connected with said jaw member in position opposite the space between the jaws so as to be displaced downwardly with respect to the jaws upon the application of the anchor to the rail and adapted by its bearing on the rail to hold the jaw member in its turned lever gripping position with respect to the flange and to prevent the jaw member from backing transversely out of gripping position.
4. A rail anchor comprising in combination a jaw member having jaws for engaging the top and bottom faces of the flange at one side of a rail and arranged for permitting a slight angular movement of the jaw member with respect to the flange about an axis extending longitudinally of the rail for exerting an effective lever grip on the flange transversely thereof, and a resilient arm connected with said jaw member in position to extend underneath the rail adapted by engagement with the bottom face of the flange at both side portions of the rail and by engagement with the side face of the flange at the free end of the arm to hold said jaw member in turned lever gripping engagement with the flange.
5. A rail anchor comprising in combination two jaw members in the form of plates in spaced relation to each other and connected at their outer edge portions by a third plate formed integrally therewith, each of said jaw members being provided with a notch in its inner edge portion providing jaws for engaging the top and bottom faces of the flange of a rail and arranged with clearance with respect to the flange at opposite sides of the effective bearing portions of the jaws for permitting a slight rotary movement about an axis extending longitudinally of the rail for exerting an effective lever grip on the flange, and an arm formed integrally with said third plate and extending between said jaw members into position opposite said notches adapted by engagement with the bottom face of the flange and by engagement with the side face of the flange at the free end of the arm to hold said jaw members in turned lever gripping engagement with the flange.
6. A rail anchor comprising in combination a jaw member adapted by rotary movement about an axis extending longitudinally of a rail to have a lever grip upon the flange of the rail at one side thereof, and an arm adapted at the end of said rotary movement of the jaw member to snap into holding engagement with the edge of the flange at the opposite side of the rail and adapted by its tensile strength to hold said jaw member in its turned gripping position.
7. A rail anchor comprising in combination a head portion having jaws for engaging the top and bottom faces of the flange at one side of a rail and adapted to be rotated about an axis extending longitudinally of the rail to exert a lever grip on said top and bottom faces, and an arm extending under the rail adapted by engagement with the opposite edge of the rail to hold said jaws in their lever gripping engagement with said flange.
8. A rail anchor comprising in combination a head portion having upper and lower jaws for engaging the top and bottom faces of the flange at one side of a rail and adapted to be rotated about an axis extending longitudinally of the rail to exert a lever grip on said top and bottom faces, and an arm connected with said head member at a substantial distance below said lower jaws and extending under the rail adapted by engagement with the opposite edge of the rail to hold said jaws in their lever gripping engagement with said flange.
9. A rail anchor comprising in combination two jaw members in spaced relation adapted by rotary movement about an axis extending longitudinally of a rail to have a lever grip upon the flange of the rail at one side thereof, and an arm extending under the rail between said jaw members and connected with said members at a distance below the rail adapted upon the rotary movement of the jaw members into their final lever gripping position to snap into holding engagement with the edge of the flange at the opposite side of the rail and adapted by its pull on the jaw members to hold them in their turned gripping position.
10. A rail anchor comprising in combination a head member having vertically rigid gripping jaws for engaging the top and bottom faces of the flange at one side of a rail, and a resilient arm connected at one end with said head member and extending under the rail with its other end turned up for engagement with the edge of the flange at the opposite side of the rail, the length of the arm and its position on the head member being

such that the arm is enabled to grip the edge of the flange at said opposite side of the rail only when the head member has been turned about a longitudinal axis so as to bring the 5 jaws into lever gripping engagement with the flange.

11. A rail anchor comprising in combination a head member having vertically rigid gripping jaws for engaging the top and bottom faces of the flange at one side of a rail and arranged to have a swinging movement with respect to the flange about an axis extending longitudinally of the rail for exerting an effective lever grip on the rail, and a 10 resilient arm connected at one end with said head member and extending under the rail, the opposite end of said arm being provided with a turned-up portion adapted to engage the bottom face of the rail when the head is 15 driven evenly into preliminary gripping position on the rail but adapted to snap into engagement with the edge of the flange of the rail when the head is turned about said longitudinal axis by pressure applied at the 20 bottom portion of the head.

12. A rail anchor comprising in combination a head member having vertically rigid gripping jaws for engaging the top and bottom faces of the flange at one side of a rail, and a resilient arm connected at one end with said head member independently of said gripping jaws and extending under the rail, the opposite end of said arm being provided with a turned-up portion adapted to engage 30 the bottom face of the rail when the head is driven evenly into preliminary gripping position on the rail but adapted to snap into holding engagement with the edge of the flange of the rail when the head is turned about a longitudinal axis by pressure applied at the bottom portion of the head and adapted thereby to hold the jaws in lever gripping engagement with the flange.

13. A rail anchor comprising in combination a head member having vertically rigid gripping jaws for engaging the top and bottom faces of the flange at one side of a rail, a resilient arm connected at one end with said head member and extending under the rail, and means carried by the arm adapted by snap engagement with the edge of the flange of the rail when the head is turned about a longitudinal axis by pressure at the bottom portion of the head to hold said head 50 against turning in the opposite direction, said arm being adapted by engagement with the bottom face of the rail adjacent to the head of the anchor to strengthen the grip of the anchor on the rail.

14. A rail anchor comprising in combination a head member having vertically rigid gripping jaws for engaging the top and bottom faces of the flange at one side of a rail, and a resilient arm formed of sheet metal connected at one end with said head member and

extending under the rail with its edge disposed toward the cross tie and with its other end bent up for engagement with the edge of the flange at the opposite side of the rail, the length of the arm and its position on the head member being such that it is enabled to grip the edge of the flange only when the head member has been turned about a longitudinal axis so as to bring the jaws into lever gripping engagement with the flange.

15. A rail anchor comprising in combination a head member having vertically rigid gripping jaws for engaging the top and bottom faces of the flange at one side of a rail, a resilient arm connected at one end with said head member and normally projecting in such direction from the head member that it is displaced downwardly upon the application of the anchor to a rail and is held by its resiliency in contact with the bottom face of the rail when the anchor is in position thereon, and means carried by the arm adapted by snap engagement with the edge of the flange of the rail when the head is given an effective lever grip on the rail by a turning movement about a longitudinal axis by pressure applied at the bottom portion of the head to hold said head against a loosening movement in the opposite direction.

16. A rail anchor comprising in combination a head member having vertically rigid gripping jaws for engaging the top and bottom faces of the flange at one side of a rail, and a resilient arm connected at one end with said head member at a point below said jaws and extending from the head member under the rail, said arm being provided with means at its opposite end adapted to snap into engagement with the edge of the flange of the rail only when the effective length of the arm is increased by a turning movement of the head about a longitudinal axis for bringing the jaws into lever gripping engagement with the flange.

17. A rail anchor comprising in combination a jaw member, a notch in the edge of said member providing jaws for engaging the top and bottom faces of the flange of the rail and arranged with clearance with respect to the flange for permitting a slight rotary movement about an axis extending longitudinally of the rail for exerting an effective lever grip on the flange, and an arm connected with said jaw member and provided with an upturned portion at its free end adapted upon the rotary movement of the jaw member into its lever gripping position to snap into holding engagement with the edge of the flange at the opposite side of the rail and adapted by such engagement to hold said jaws in tight gripping engagement with the rail.

18. A rail anchor comprising in combination a jaw member, a notch in the edge of said member providing jaws for engaging the top

and bottom faces of the flange of the rail, said notch being arranged so that the end of the effective portion of the upper jaw is located only a short distance to one side of the opposite end of the effective portion of the lower jaw whereby a rotary movement of the jaw member produces an effective lever grip on the flange, and an arm connected with said jaw member and provided with an upturned portion at its free end adapted to engage the bottom face of the rail when the jaw member is driven evenly into gripping engagement with the flange but adapted upon said rotary movement of the jaw member to snap into holding engagement with the edge of the flange at the opposite side of the rail for holding said jaw member in tight gripping engagement with the rail.

19. A rail anchor comprising in combination a sheet metal plate, two jaw members formed integrally with said plate and turned at an angle with respect thereto into spaced relation to each other, notches in the edges of said members providing jaws for engaging the top and bottom faces of the flange of the rail and arranged with clearance with respect to the flange for permitting a slight rotary movement about an axis extending longitudinally of the rail for exerting an effective lever grip on the flange, and an arm formed integrally with said first named plate and provided with an upturned portion at its free end adapted upon the rotary movement of the jaw members into their lever gripping position to snap into holding engagement with the edge of the flange at the opposite side of the rail and adapted by such engagement to hold said jaws in tight lever gripping engagement with the rail.

20. A rail anchor comprising in combination two jaw members connected together at corresponding edges in spaced relation to each other, each member having gripping jaws for engaging the top and bottom faces of the flange at one side of a rail, and an arm connected with said jaw members and extending under the rail when the anchor is applied thereto, said arm having an upturned portion at its free end adapted by engagement with the edge of the flange at the opposite side of the rail to hold said jaws in tight gripping engagement with the rail, said jaw members being normally convergent toward their connected edges so that when one

of said jaw members is displaced toward the other member the jaws are further tightened upon the rail.

21. A rail anchor comprising in combination a sheet metal plate, two jaw members formed integrally with said plate and turned at an angle with respect thereto into spaced relation to each other converging toward the plate, notches in the edges of said members providing jaws for engaging the top and bottom faces of the flange of the rail, and a resilient arm connected with said plate and provided with an upturned portion at its free end adapted by engagement with the edge of the flange at the opposite side of the rail to hold said jaws in tight gripping engagement with the rail.

22. A rail anchor comprising in combination a sheet metal plate, an arm connected with said plate and extending from one face thereof, jaw members formed integrally with said plate and standing on opposite sides of the arm in divergent position with respect to the arm, said jaw members being provided with notches in corresponding edges forming jaws for engaging the top and bottom faces of the flange of a rail, and an upturned portion at the free end of said arm adapted by engagement with the edge of the flange at the opposite side of the rail to hold said jaws in tight gripping engagement with the rail.

23. A rail anchor comprising in combination a sheet metal plate, sheet metal jaw members formed integrally with said first named plate and bent into spaced relation to each other at one face of the plate, said jaw members being provided with notches in their free edges forming jaws for engaging the top and bottom faces of the flange of a rail, an arm formed integrally with said plate and bent at an angle thereto so as to extend between said jaw members and under the rail in flatwise position with respect to the rail, and an upturned portion at the free end of the arm adapted when the jaws are driven evenly into preliminary gripping engagement with the flange to engage the bottom face of the rail but adapted when pressure is applied to the bottom portions of the jaw members to snap into engagement with the flange of the rail and adapted by such engagement to hold the jaws in gripping engagement with the rail.
